[57] ABSTRACT

A simulated log-rolling device for use out of water that includes a pair of upright supports that carry a rotating drum therebetween which rotates about a horizontal axis. The outer surface of the drum is molded to represent bark on a tree. The drum carries water within it and the drum includes a series of internal baffles that operate in conjunction with the water to retard rotation of the drum. Structurally, the baffles extend lengthwise of the drum and further extend inwardly toward but fall short of the axis of rotation of the drum, whereby, as the drum rotates, the water is forced to flow around the inner ends of the baffles thus causing the retarded rotation of the drum.

FIG. I

FIG. 2

FIG. 3

SIMULATED LOG-ROLLING DEVICE WITH INWARDLY EXTENDING BAFFLE MEMBERS

BACKGROUND OF THE INVENTION

Heretofore it has been known to provide log-rolling toys. For example, in one U.S. patent, there is provided an actual log that is supported on land. However, the problem with this type of arrangement is that there is no sound of movement of water which people associate with log-rolling contests. Other devices as are shown in other U.S. patents provide for log-rolling devices or toys that are floatable in water. The problem with these types of devices is, of course, that a body of water must be provided in order to use them.

SUMMARY OF THE INVENTION

With the above in mind, it is the primary object of the present invention to provide a simulated log-rolling toy for use out of water and which has the splashing sound characteristic of an actual log in the water. It is proposed in the present invention to provide an elongated horizontally disposed tank which may be supported at opposite ends above the ground and which has a bark-like surface molded thereon so as to appear like a log. The tank has provided internally thereof a series of baffles. It is anticipated that the tank will be partially filled with water and the baffles will operate to retard rotation of the tank as people stand on it for purposes of rotating it and also to strike the water so that the toy will give the characteristic sound of a log rolling or thrashing in water.

More specifically, it is the purpose of the present invention to provide an elongated tank that is carried on upright supports at opposite ends so that it will rotate. Internally of the tank there are provided radially inwardly projecting baffles that have their inner terminal ends spaced from the axis of rotation. Thus, as the tank rotates, the water must flow over the inner ends of the baffles.

BRIEF DESCRIPTION OF THE DRAWINGS

FIG. 1 is a perspective view taken at one end and to the side of the log-rolling toy.

FIG. 2 is an enlarged sectional view taken substantially along the line 2-2 of FIG. 1.

FIG. 3 is a sectional view taken substantially along the line 3-3 of FIG. 2.

DESCRIPTION OF THE PREFERRED EMBODIMENT

The toy device includes a pair of spaced apart upright supports 9, 10 that includes upper couplings 11, 12, respectively. The support at the left end of the device includes a pair of depending legs 13, 14 that fit at their upper ends into the coupler 11 and which may be anchored as at 15, 16 in cement in the ground. The right end support 10 includes a pair of legs 17, 18 that depend from the coupler 12 and have their lower ends anchored in cement paddings 19, 20 placed in the ground. The legs 13, 14 and 17, 18 support the couplers 11, 12 at between one and two feet above the ground. Extending between the upright supports 9, 10 and specifically the couplers 11, 12 is an elongated rod 21. The couplers 11, 12 have horizontal extensions 22, 23 that face one another and receive opposite ends of the horizontal rod 21. Set screws 24, 25 are provided in the extensions 22, 23 for fixing the rod 21 in the respective ends. The

rod 21 serves as a horizontal pivot for the entire simulated log indicated in its entirety by the reference numeral 26.

The simulated log is composed of an elongated cylindrical portion or tank member 30 that is generally formed about the axis of rotation as indicated by the rod 21. The tank member 30 has a molded outer surface 31 simulated to represent bark on a tree. Also, the simulations 31 serve as frictional surface for one standing on the log and desiring to rotate it. The tank 30 has opposite radially extending ends 32, 33 that are sealed against the cylindrical portion 30 and which make the tank substantially waterproof. The ends 32, 33 have integral inwardly extending hubs 34, 35 fitted to rotate on the rod 21 and serving to journal the entire simulated log 26 on the rod 21. The end 32 has a detachable plug 36 that closes an opening in the end 32 so that water or liquid may be inserted or removed from the log structure 26. Integral with and extending inwardly from the outer cylindrical casing 30 are three baffles 37 that have inner ends 38 terminating outwardly of the rod 21. The baffles 37 extend the full length of the simulated roll and the ends 32, 33 are fixed to the ends of the baffles as well as the cylinder casing 30. Thus, the baffles 37 serve to rigidify and strengthen the entire structure.

Outwardly of the ends 32, 33, collars 40, 41 are provided on the rod 21 and bolts 42, 43 are provided in the collars so as to lock the collars on the rod 21 and to, of course, bear against opposite ends 32, 33 of the simulated log 26 so as to prevent the log from moving axially on the rod 21.

The simulated log 26 may be between one and three feet in diameter and preferably between one and one-half feet and two and one-half feet in diameter. It is supported so that it is relatively close to the ground so that if one feels himself slipping while standing on the log he may jump from the log without injury. In operation, the plug 36 is removed and the log is filled with water substantially to the level as shown in FIGS. 2 and 3. The plug 36 is then inserted so as to close the opening and the log is ready for operation. The baffles 37 contacting the water as the log rotates will retard rotation of the log so that the log will have the feel of one that is actually in water. Also, the sound of water within the log will simulate the sound of a log as it actually rotates in water.

It should also be recognized that the triangular-type supports 9, 10 at opposite ends of the log-rolling toy are such that they could be located in a recreation room or within a building or gymnasium. The legs 13, 14 and 17, 18 would then have suitable pads on their lower ends so that they could be carried on the floor. Thus, when reference is made to groundborne with respect to the logging device, it should be recognized that this is meant to include the indirect type of groundborne such as would occur by a floor which is in turn carried on the ground.

I claim:

1. A simulated log-rolling device for use out of water comprising: a pair of spaced apart and ground-borne upright supports; an elongated horizontal liquid-carrying rigid tank structure supported on the supports and including a horizontal elongated rigid tank supported to rotate about a substantially horizontal axis and sealed at opposite ends; a detachable plug on the tank for passing liquid to and from the tank; and rigid

baffles fixed to and extending lengthwise of the tank and extending radially inwardly with respect to the inner surface of the tank toward inner ends falling a substantial distance short of said axis of rotation so that water may freely flow around said inner ends as the tank rotates.

2. The invention as set forth in claim 1 in which the tank is cylindrical shaped and has an outer surface formed to simulate bark on a tree.

3. The invention as set forth in claim 1 in which the tank structure includes an elongated rod having opposite ends fixed to the respective uprights above the ground, and the opposite ends of said tank have journal means thereon journaled on the rod that supports the tank to rotate on said rod about said horizontal axis.

4. The invention as set forth in claim 3 in which the rod is round, the ends of the tank are radially extending with respect to the rod and the journal means are integral with the ends and extend axially within the tank, and further characterized by means externally of the tank at said ends for limiting axial movement of the tank on the rod.

5. A simulated log-rolling device composed of an elongated rigid liquid-carrying tank structure having an outer roughened surface and rigid internal baffle members extending lengthwise of the tank structure, said

baffle members extending inwardly with respect to the inner surface of the tank structure toward inner ends falling a substantial distance short of the longitudinal center of the tank structure so that water may freely flow around said inner ends upon rotation of the tank structure, said tank structure having horizontal journal means at opposite ends thereof and ground borne means including vertical supports at opposite ends of the tank structure having supports engaging said journal means and for supporting said tank structure above the ground and for rotation about a substantially horizontal axis; and a detachable plug on the tank structure for passing liquid to and from the tank structure and internally thereof.

10 6. The simulated log-rolling device as set forth in claim 5 in which the supports support the tank structure so that the underside thereof is closely adjacent to but above the ground.

15 7. The simulated log-rolling device as set forth in claim 6 in which the tank structure is in size between one and three feet across the axis.

20 8. The simulated log-rolling device as set forth in claim 6 in which the tank structure is in size preferably between one and one-half feet and two and one-half feet across the axis.
